UNITED STATES PATENT OFFICE

157,138

SOFT SPEAKER FOR DICTATING MACHINES

Florian J. Fox, Stratford, Harry A. Williams,
Trumbull Township, Fairfield County, and
Ralph A. Sherman, Jr., Fairfield, Conn.

Application July 22, 1949, Serial No. 4,078

Term of patent 14 years

(Cl. D26—14)

To all whom it may concern:

Be it known that we, Florian J. Fox, Harry A. Williams, and Ralph A. Sherman, Jr., all citizens of the United States, residing, respectively, in the town of Stratford, and township of Trumbull, and the town of Fairfield, all in the county of Fairfield and the State of Connecticut, have invented a new, original, and ornamental Design for a Soft Speaker for Dictating Machines, of which the following is the specification, reference being had to the accompanying drawings, forming part thereof.

Figure 1 is a front elevation of a soft speaker for dictating machines, showing our new design;

Figure 2 is an elevation of the left-hand side thereof; and

Figure 3 is a rear elevation thereof.

The elevation of the right-hand side of the soft speaker for dictating machines shown in Figure 1 appears the same as the elevation shown in Figure 2.

We claim:

The ornamental design for a soft speaker for dictating machines, substantially as shown and described.

FLORIAN J. FOX.
HARRY A. WILLIAMS.
RALPH A. SHERMAN, JR.
